Sam Landorf and Company, Inc., New York,
N. Y.

Application February 12, 1953, Serial No. 23,570

Term of patent 3½ years

(Cl. D3—26)

To all whom it may concern:

Be it known that I, Howard Landorf, a citizen of the United States, residing at New York city, in the county and State of New York, have invented a new, original, and ornamental Design for a Child's Dress, of which the following is a specification; reference being had to the accompanying drawing, forming a part thereof.

Fig. 1 is a front elevational view of a child's dress, showing my new design.

Fig. 2 is a rear view thereof.

I claim:

The ornamental design for a child's dress, substantially as shown.

HOWARD LANDORF.
